W. K. TROTMAN.
DANDY ROLL AND OTHER LIKE DEVICES SUCH AS CYLINDER MOLDS, &c.
APPLICATION FILED JUNE 19, 1915.

1,244,562.

Patented Oct. 30, 1917.

INVENTOR

Walter Knowles Trotman

UNITED STATES PATENT OFFICE.

WALTER KNOWLES TROTMAN, OF HOLYOKE, MASSACHUSETTS, ASSIGNOR OF ONE-HALF
TO CHARLES DRURY JACOBS, OF NEW YORK, N. Y.

DANDY-ROLL AND OTHER LIKE DEVICES SUCH AS CYLINDER-MOLDS, &c.

1,244,562.

Specification of Letters Patent. Patented Oct. 30, 1917.

Application filed June 19, 1915. Serial No. 35,159.

To all whom it may concern:

Be it known that I, WALTER KNOWLES TROTMAN, a subject of the King of England, at present a resident of Holyoke, in the 5 county of Hampden and State of Massachusetts, have invented new and useful Improvements in Dandy-Rolls and other like Devices such as Cylinder-Molds, &c., of which the following is a specification.

10 My invention relates to dandy rolls, cylinder-molds, etc., in which the outer covering may be mounted upon the frame without the common sewing operation and in which the same may be tightly strained and drawn 15 into the desired fixed position and to mechanism wherein separate and independent sections may be mounted in place.

I accomplish the objects of my invention by the construction herein shown and 20 described.

In the accompanying drawings in which like letters of reference indicate like parts,

Figure 1 is a perspective view of a section of a dandy roll having a part of one head; 25 the wire frame and the cover broken away, thus disclosing the interior mechanism employed for drawing the edges of the cover into place.

Fig. 2 is a detached view of a part of such 30 mechanism on a larger scale.

Fig. 3 is a plan view of the angularly arranged tightening block and a part of its operating mechanism, and,

Figs. 4 and 5 are edge views of the 35 detachable clip provided cover portions.

The construction and operation of my device will be readily understood on reference to the drawings in connection herewith.

The dandy roll frame as illustrated in this 40 application comprises a suitable shaft *a* having heads *b* and spiders *c*, upon the peripheries of which are mounted the parallel rods *d* and the rings or helixly wound wires *e*. The cover *f* formed of fine woven wire has 45 secured to its meeting edges strips *g*, which strips have depending clips *h* adapted to engage the wires *e*. A line or set of blocks or strips *i* are preferably permanently secured to the frame wires *e* so that the strips

50 *g* and depending clips *h* will abut against the strips *i*. A rock shaft *j* is mounted in suitable bearings and has fixed to it a block or member *k*, the outer edge of which bears against the strip *g* and against the clips *h* 55 so that if the rock shaft *k* is turned or rocked

in one direction the edge with which the block *k* is in contact is carried toward the adjacent edge of the cover and held firmly in place.

Whenever it is desired to loosen and remove the cover, the rock shaft *j* is rotated a short distance in the opposite direction, thus loosening and relieving from strain the edge to which the strip *g* is attached, so that the cover may be readily removed and another 60 like cover substituted.

For convenient operation of the rock shaft *j* I provide a threaded rod *l* having threaded connection with a crank provided member *m*, and also secured to an angular block 70 *n* which block has movement in the frame *o* so that if the block be moved in one direction the frame will be carried to the right and if moved in the opposite direction the frame will be moved to the left. The frame 75 *o* has anti-friction rolls *p* and is provided with a projection *r* the latter being in engagement with the rock shaft *j* so that as the frame *o* is moved by reason of moving the block *n* the rock shaft *j* will be rotated 80 85 in a direction dependent upon the direction of the movement of the block *n* and thus the cover tightened on the frame or loosened for removal therefrom. For the purposes of accurate adjustment the rod *l* is threaded adjacent its connection with the block *n* so 90 that it may be adjusted and permanently fixed in the desired position and its necessary field of operation controlled by the crank provided member *m*. A most convenient 95

means of arranging for such adjustment between the rod *l* and block *n* comprises the employment of nuts *s*. To avoid friction in the movement of the block *n* in the frame *o* I provide anti-friction rolls *p* against which 95 the edges of the block *n* bear.

If the cover is made of segments or sections instead of one continuous piece, then each section should be provided with an independent rock shaft and independent mechanism for operating the same.

With this construction it will readily be seen that covers either continuous or in separate sections may be mounted upon a dandy roll or cylinder frame without the expensive 105 and tedious method of sewing the same permanently in place heretofore employed, and that the cover portions may be easily mounted in place and removed therefrom without the delay heretofore required and that a 110

single frame may be employed for use in connection with an unlimited number of covers while heretofore it has been common to employ a frame with each cover.

5 Having therefore described my invention what I claim as new and desire to secure by Letters Patent is:—

1. In a dandy roll or cylinder roll a suitable frame, a cover section reinforced at its 10 edges by having flat metal strips secured thereto, means to engage the edge portions of the cover and drawing the same toward each other by a circumferential movement and means for operating the mechanism for 15 so drawing the edges together whereby the covers are held in place or may be removed at will.

2. The combination in a dandy roll of a 20 suitable supporting shaft, a suitable frame mounted thereon, a rock shaft mounted in the frame, a cover having engaging means at its meeting edges, a member mounted on the rock shaft to engage the cover edge portions and draw them toward each other, and 25 means comprising a longitudinally moving member to rotate the rock shaft substantially as shown.

3. In a dandy roll a suitable shaft and frame, a rock shaft, means projecting therefrom to engage the engaging edge portions 30 of the cover, a cover provided with members for engagement with the engaging member on the rock shaft, a sliding angular block, means to move said block, and means to impart the motion caused by movement 35 of said block to the rock shaft, substantially as shown.

4. In a dandy roll a suitable frame, a removable cover, a frame *o* having slidingly mounted therein a block *n*, a threaded member engaging the block *n* and adapted to move the same longitudinally of the dandy roll, a rock shaft *j*, operative connection between the frame *o* and rock shaft *j* and engaging means between the rock shaft *j* and 45 the edge of the cover, substantially as shown.

5. A roll comprising a suitable frame, a suitable cover provided at its meeting edge portion with clips *h* and means mounted in the roll to draw said meeting edges together 50 by circumferential movement, substantially as shown.

WALTER KNOWLES TROTMAN.
